United States Patent Office

Des. 181,918
Patented Jan. 21, 1958

181,918

BOTTLE

Egmont Arens, New York, N. Y., assignor to Anderson,
Clayton & Co., Houston, Tex., a corporation of Delaware

Application November 16, 1956, Serial No. 43,792

Term of patent 14 years

(Cl. D58—8)

Fig. 1.

Fig. 2.

Figure 1 is a side elevational view of a bottle showing my new design, the ornamental detail being continuous around the top portion of the bottle; and

I claim:

The ornamental design for a bottle, as shown.
